LIQUID DISPENSING APPARATUS

Richard R. Trexler, Evanston, Ill.

Application December 19, 1938, Serial No. 246,544

3 Claims. (Cl. 221—95)

This invention relates to liquid dispensing apparatus, and more particularly to cost indicating and registering mechanism therefor.

It is an object of the invention to provide improved cost registering and indicating mechanism particularly adapted for use with gasoline dispensing apparatus; and more specifically to provide an improved and simplified change speed gearing construction for use with such devices.

Further objects of the invention are to provide simplified and more readily operable adjustment means for changing the speed ratio of the change speed gearing, whereby to permit the calculation and registration of the cost of the dispensed liquid at different preselected unit prices; and to provide improved and simplified setting and indicating mechanisms in association therewith.

The mechanism hereinafter specifically set forth embodies a liquid dispensing apparatus for gasoline, and in accordance with the invention a change speed gearing of the cone gear type is provided which will permit price calculation in increments of one-tenth of a cent over the full range through which the price of gasoline may be expected to fluctuate. Only two take-off gear trains are provided for cooperation with the cone gears, thereby simplifying the gearing mechanism and permitting the use of simplified price setting and price indicating means.

Other objects, advantages and features of the invention will be apparent from the following specification when taken in connection with the accompanying drawings wherein one preferred embodiment of the invention is illustrated.

In the drawings, wherein like reference numerals refer to like parts throughout:

Fig. 1 is a general assembly, partly in section, of a liquid dispensing apparatus for gasoline embodying the invention.

Fig. 2 is a partial sectional view of the apparatus shown in Fig. 1, on the line 2—2 thereof.

Fig. 3 is a transverse sectional view on an enlarged scale, taken on the line 3—3 of Fig. 1.

Fig. 4 is a detail view of the cone gearing, taken on the line 4—4 of Fig. 5.

Fig. 5 is a transverse view of the gearing, on the line 5—5 of Fig. 4.

Fig. 6 is a view of the differential and gearing mechanisms, Fig. 6 being a continuation of the upper part of the mechanism shown in Fig. 4.

Fig. 7 is a transverse view of the differential gearing, being taken on the line 7—7 of Fig. 6, and

Figs. 8 and 9 are detail views of one of the take-off gear trains which cooperate with the cone gearing, the gear train being shown in inoperative position, Fig. 9 being taken on the line 9—9 of Fig. 8.

Referring to Fig. 1, the apparatus illustrated comprises an underground tank 10 adapted to receive the liquid to be dispensed, which will be gasoline in the particular instance shown. A pipe 11 leads from the underground tank to a pump 12 driven by suitable gearing 13 from an electric motor or other power source 14. The outlet of the pump leads, by means of a pipe 15, to an air release mechanism 16 which has its outlet connected to a pipe 17 leading to a meter 18. The outlet of the meter is connected to a pipe 19 leading through a sight glass to a flexible hose 21 terminating in a valve controlled dispensing nozzle 22. The dispensing nozzle is adapted to be supported upon a support hook 23 which has its inner end connected to a link 24 leading to a switch 25 for controlling the current to the electric motor 14. The above elements may be of the usual type provided in gasoline liquid dispensing apparatus. In operation the pump 12, driven by the motor 14, pumps the gasoline from the underground tank 10 through the air release mechanism 16, the meter 18, the sight glass 20, and then through the dispensing nozzle 22. In apparatus of this type the motor 14 is operated only upon manipulation of the hook 23, after removal of the hose nozzle. The liquid passes through the meter 18 only when the nozzle valve is open, any excess liquid pumped by the pump 12 being bypassed back to the inlet side of the pump.

In accordance with the invention a shaft 27, driven by the meter 18 in proportion to the liquid flow, is connected to a bank of cone gears 28. The gears may conveniently be die-cast in the form of a single casting, if desired. The shaft 27 extends upwardly beyond the cone gears and terminates in a bevel gear 29 arranged to drive a bevel gear 30 secured to a shaft 31. The shaft 31 is adapted to drive a gearing 32 connected to a volume register 33 for indicating the number of gallons of liquid dispensed. A sleeve 34 loosely journaled on shaft 27 carries a bevel gear 35 operating a bevel gear 36 secured to a shaft 37. This shaft drives a gearing 38 adapted to operate a cost register 39 for indicating the total cost of the dispensed liquid. The particular form of the registers 33 and 39 constitutes no part of the present invention. 55 They may be of any suitable construction, for

example of the type shown in the patent to E. J. Svenson, Liquid handling mechanism, No. 2,117,750, dated May 17, 1938, and are preferably provided with the usual forms of resetting mechanisms and the like. The present invention concerns more particularly the means for driving the sleeve 34 which operates the cost register, and the unit price indicating mechanism, adapted to be exhibited through the housing, as shown at 40.

Referring to Figs. 4 and 5, and particularly to Fig. 4, in the preferred embodiment of the invention illustrated, the cone bank 28 comprises forty-two gears, the smallest gear 41 at the top of the cone being an 8-tooth gear and the largest gear 42 at the bottom of the cone being a 90-tooth gear. The gears from the smaller to the larger end of the cone are of progressively increasing size in increments of two teeth. That is, the gear 43 immediately adjacent the gear 41 has ten teeth, the gear 44 twelve teeth, the gear 45 fourteen teeth and so on. This bank of gears may be used to calculate the gasoline cost from 4¢ to 45.9¢ per gallon in increments of one-tenth of a cent, as will be later shown.

The cone gears are adapted to operate two take-off gears 46 and 47, the gear 46 being the "cents" gear and the gear 47 being used for calculating "tenths of cents." The gear 46 is rotatably mounted upon a shaft 48 carried at the inner end of a bracket 49 rotatably and slidably journaled upon an upstanding shaft 50. The bracket also carries a gear 51 in geared engagement with the gear 46. Gear 51 may be freely moved longitudinally of the shaft 50 with the bracket 49, but any rotational movement imparted to gear 51 correspondingly rotates the shaft 50 by means of the key connection 50. The outer end of the bracket carries an extending pin 53 which serves as a handle for positioning the bracket longitudinally and rotatably of the shaft 50 whereby to bring the gear 46 into meshing engagement with any selected gear upon the cone bank 28. A curved locking plate 54 of triangular shape, as perhaps best shown in Fig. 4, is arranged adjacent the bracket 49, the plate being provided with a series of holes 55 adapted to receive a pin 56 removably carried by the outer end of the bracket. By means of the handle 53, the bracket may be moved longitudinally and rotatably of shaft 50 to bring the gear 46 into engagement with any selected gear on the cone bank, and the openings 55 in the locking plate 54 are so spaced and arranged that the bracket may be locked in each of its selective operative positions by passing the removable pin 56 through the corresponding opening 55 and into the end of the bracket. When it is desired to entirely disengage the take-off gear 46 from the cone bank, the bracket is lowered to its extreme position and then rotated clockwise, as viewed in Fig. 5, to cause the teeth of the gear wheel 46 to engage a locking tooth 57. The bracket may be locked in such clockwise position by causing the pin 56 to engage with a notch 58 formed in locking plate 54 for this purpose.

The mounting for the "tenths" take-off gear 47 is substantially similar and comprises a bracket 59 rotatably and slidably mounted upon a shaft 60. The bracket carried a handle 61 and a locking pin 62 adapted to cooperate with openings 63 formed in a locking plate 64. A gear 65 keyed to the shaft 60 meshes with the gear 47. The bracket may be rotatably and longitudinally adjusted with respect to the shaft 60 to bring

the take-off gear 47 into selective engagement with the cone gears, and in its lowermost position the bracket is rotatable clockwise to disengage the take-off gear from the cone gears and bring it into engagement with a stationary locking tooth 66, all as previously described. In Figs. 8 and 9 the parts are shown with the gear 47 and tooth 66 in locking engagement. While the mounting constructions for the take-off gears 46 and 47 are generally similar, in the case of the "tenths" gear 47 the arrangement is such that the take-off gear may be engaged with only certain of the gears of the cone bank. More specifically take-off gear 47 may be engaged with cone gear 43 having ten teeth, cone gear 67 having twenty teeth, gear 68 having thirty teeth, and gears 69, 70, 71, 72, 73 and 42 having forty, fifty, sixty, seventy, eighty and ninety teeth respectively. The openings 63 in the locking plate 64 are so positioned as to permit this manner of engagement.

The mechanism operated by the rotation of shafts 50 and 60 is best shown in Figs. 6 and 7. This mechanism comprises a differential gearing construction by which the movement of shafts 50 and 60 is combined in predetermined ratio, the combined movement being transmitted to the sleeve 34 which operates the cost register. The "tenths" shaft 60 carries a gear 75 at its upper end, in mesh with a gear 76 loosely journaled on the shaft 27. A gear 77 is integral with gear 76, the two gears being connected by a sleeve 78. The "tens" shaft 50 carries a gear 79 at its upper end in mesh with a gear 80 loosely journaled on the sleeve 78. Gear 80 is provided with a pair of oppositely extending arms 81 and 82 carrying shafts 83 and 84 respectively. Shaft 83 carries a pair of gears 85 and 86 which rotate as a unit upon the shaft. Similarly shaft 84 carries two gears 87 and 88 rotatable as a unit. Gears 81 and 85 both mesh with the gear 77, whereas gears 86 and 88 both mesh with a gear 89 formed as an integral part of the driving sleeve 34. The above described mechanism constitutes a differential gearing for combining the movements of the shafts 50 and 60, and transmitting the combined movement to the sleeve 34. Rotary motion imparted to gear 76 by the gear 75 causes the rotation of gear 77. Rotary motion imparted to the gear 80 by gear 79 causes the bodily or planetary movement of gears 85 and 87 around gear 77. The resultant movement which will be imparted to gear 89 through gears 86 and 88 is the summation of the movements of the two sets of gearing.

In operation as the cone bank 28 is rotated by the meter shaft, rotation will be imparted to the take-off gears 46 and 47 at a speed determined by the size of the gears on the cone with which the take-off gears are selectively engaged. The rotary movements of gears 46 and 47 are transmitted to the shafts 50 and 60 and then through the differential gearing to the cost sleeve 34. The gear ratio of the differential gearing is 50 to 1. That is, the movement which will be imparted to sleeve 34 when the "cents" take-off gear 46 is engaged with any given gear of the cone bank will be fifty times as great as the movement which will be imparted to the sleeve if the "tenths" gear 47 were engaged with the same cone gear. If the "tenths" gear 47 is engaged with the smallest gear of the cone bank with which it is engageable, the 10-tooth gear 43, the proportioning of the parts is such that one-tenth of a cent will be registered upon the cost

register 39 when one gallon of liquid has passed through the meter 18. The cost of the gasoline is thus computed at one-tenth of a cent per gallon. If the gear 41 is engaged with its next larger engageable gear, gear 67 having twenty teeth, the cost register will be driven twice as fast, computation being made at two-tenths of a cent per gallon. Similarly gear 41 may be selectively engaged with cone gears 68, 69, 70, etc. to compute at three-tenths, four-tenths, five-tenths etc. per gallon up to and including computation at nine-tenths of a cent per gallon when the take-off gear 47 is meshed with the largest gear 42 having ninety teeth. If the "cents" gear 46 is meshed with gear 43, computation will be made at 5¢ per gallon, fifty times the one-tenth computation which is made when take-off gear 47 is meshed with this same cone gear. If the "cents" take-off gear 48 is meshed with the smallest cone gear 41, having eight teeth, computation will be made at 4¢ per gallon. Similarly the gear 46 may be selectively engaged with any of the cone gears from the smallest gear 41 to the largest gear 42 to compute from a range of 4¢ to 45¢ inclusive. If both take-off gears 46 and 47 are engaged with the cone gears, the movement imparted to sleeve 34 will be the sum of the two shaft movements. In the position shown in Fig. 4 computation will be made at 10.8¢ per gallon. When it is desired to compute in even cents, the "tenths" take-off gear 47 is disengaged from the cone bank and locked to its locking tooth 68.

It will be seen that by means of the mechanism provided computation may be made from 4¢ to 45.9¢ per gallon in one-tenth of a cent increments, which is more than ample for the normal price fluctuation of retail gasoline. At the same time only two take-off gearing mechanisms for cooperation with the cone bank are provided. Accordingly it is necessary to provide but a single differential gearing, materially simplifying the mechanism as compared with devices employing three take-off gear trains and two differential mechanisms. Further, the setting of price by the operator is materially simplified, it being necessary merely to set two take-off gears, one for the whole "cents," and one for the "tenths of cents." Suitable designations may be placed opposite the locking holes 55 and 63. To compute at 18.6¢ per gallon the operator would merely be required to set the "cents" gear to the "18" position and the "tenths" gear to the "6" position. All confusion incident to the setting of two separate shafts to compute the 18¢ increment is eliminated. The smallest gear which it is necessary to provide is the 8-tooth gear 41, which may be feasibly manufactured and which will impart uniform speed to the take-off gear. The largest gear provided is the gear 42 having ninety teeth, which is not too large for convenient assembly within the housing.

The unit price indicating mechanism is best shown in Figs. 2, 3, 4 and 6. Referring to Fig. 6, a pair of sleeves 90 and 91 are loosely journaled on the upper ends of the shafts 50 and 60 respectively. A collar 92 is secured to the lower portion of sleeve 90, which collar has a radially extending projection 93 terminating in a vertically extending slotted arm 94. The handle 53 extends through the slot in this arm, as best shown in Figs. 4 and 5. As the take-off gear is selectively engaged with the different vertical gears of the cone bank, the handle 53 assumes different radial positions corresponding to the

5 diameter of the particular cone gear engaged. In other words, handle 53 has a given radial position for its engagement with each cone gear. Due to the connection between the handle 53 and the arm 94, the positioning of the handle will be transmitted to the sleeve 90, so that the sleeve will have a predetermined position corresponding to each engaged cone gear.

10 A gear 95 is secured to the upper end of sleeve 90. This gear meshes with a smaller gear 96 having a gear 97 integral therewith. The gear 97 meshes with a smaller gear 98 to which a tape drum 99 is secured. Due to the gearing connection 95, 96, 97 and 98, a partial revolution of the sleeve 90 will cause several rotations of the tape drum 99. A tape 100 is arranged on the drum 99, and leads from the drum around positioning pins 101 past a window 102 to a take-up drum 103. The take-up drum is provided with a spring mechanism for keeping the tape tight. The tape drum 99 is provided with a second tape 104 arranged above the tape 100. The tape 104 leads past a window 105 arranged on the opposite side of the housing to a sprung-urged take-up roller 106. The tapes 100 and 104 carry appropriate "cents" price designations in a position to be exhibited through the windows 102 and 105. It will be seen that as the sleeve 90 is positioned from the handle 53, the tape drum 99 will be rotated to bring the proper price designation to a display position through the windows corresponding to the price position of the handle 53. To insure the proper positioning of the tapes, the drum 99 may be provided on its lower surface with a series of spaced depressions 107 adapted to be engaged by a spring-pressed pin 108, as best shown in Figs. 2 and 6. When the pin 108 engages one of the depressions, the designations on the tapes will be properly centered with respect to the windows 102 and 105.

15 The mechanism for indicating the "tenths of cents" is substantially similar and comprises a slotted arm 109 secured to the lower portion of sleeve 91 and adapted to be positioned by the handle 61 for the "tenths" take-off gear 47. The upper end of sleeve 91 carries a gear 110 in engagement with a smaller gear 111 secured to a tape drum 112, the arrangement being such that a partial revolution of the sleeve 91 causes the appropriate required movement of the tape drum. The drum carries an upper tape 113 leading past window 105 to a take-up roller 114, and a lower tape 115 which leads under tape 104 around positioning pins 116, and past the window 102 to a take-up drum 111. Inasmuch as tape 115 is below tape 104, no interference will result. Tapes 113 and 115 carry the "tenths of cents" indication and are appropriately displayed in the windows 102 and 105 as the "tenths" take-off gear is positioned. Drum 112 may be positioned with positioning mechanism 118, 119 as in the case of drum 99.

20 As best shown in Fig. 1, the "cents" designations will appear through one window and the "tenths of cents" designations through an adjacent window in the housing. The tapes permit the two designations to be brought into close proximity so that they may be easily read. 25 Further, in view of the fact that all of the whole cents are controlled from a single take-off gear mechanism, a single tape may be used to indicate the whole cents as distinguished from an arrangement employing two take-off gear mechanisms for the cents wherein the parts of any

cent designation having two figures must be controlled from separate mechanisms. The arrangement of the entire cents designation upon a single tape or dial facilitates accurate reading.

It is obvious that various changes may be made in the specific embodiment set forth without departing from the spirit of the invention. The invention is accordingly not to be limited to the specific embodiment shown and described, but only as indicated in the following claims.

The invention is hereby claimed as follows:

1. A liquid dispensing apparatus having provisions for measuring liquid and calculating the cost thereof in increments of one-tenth of a cent over a price range exceeding a differential of ten cents, said apparatus comprising a meter operated in accordance with the amount of liquid dispensed, a cost register driven by the meter, and change speed gearing mechanism interposed in the driving connections between the meter and the cost register, said change speed gearing having a bank of cone gears of continuously increasing size from one end to the other thereof and only two take-off gears adapted for cooperation therewith.

2. A liquid dispensing apparatus having provisions for measuring liquid and calculating the cost thereof in increments of one-tenth of a cent over a price range exceeding a differential of ten cents, said apparatus comprising a meter operated in accordance with the amount of

liquid dispensed, a cost register driven by the meter, change speed gearing mechanism interposed in the driving connections between the meter and the cost register, said change speed gearing having a bank of cone gears of continuously increasing size from one end to the other thereof and only two take-off gears adapted for cooperation therewith, and a pair of selectively operable price setting mechanisms for setting said take-off gears, one setting mechanism being cooperable with each gear.

3. A liquid dispensing apparatus having provisions for measuring liquid and calculating the cost thereof in increments of one-tenth of a cent over a price range exceeding a differential of ten cents, said apparatus comprising a meter operated in accordance with the amount of liquid dispensed, a cost register driven by the meter, change speed gearing mechanism interposed in the driving connections between the meter and the cost register, said change speed gearing having a bank of cone gears of continuously increasing size from one end to the other thereof and only two take-off gears adapted for cooperation therewith, and a pair of unit price indicating dials controlled by the position of the take-off gears with respect to the cone bank, one dial being operated by each take-off gear.

RICHARD R. TREXLER.
